(57) **CLAIM**

The ornamental design for a combined product display and storage container, as shown and described.

DESCRIPTION

FIG. 1 is a perspective view of a first embodiment for a combined product display and storage container.

FIG. 2 is a right-side elevation view of the product display and storage container shown in FIG. 1.

FIG. 3 is a left-side elevation view of the product display and storage container shown in FIG. 1.

FIG. 4 is a front elevation view of the product display and storage container shown in FIG. 1.

FIG. 5 is a rear elevation view of the product display and storage container shown in FIG. 1.

FIG. 6 is a top plan view of the product display and storage container shown in FIG. 1.

FIG. 7 is a bottom plan view of the product display and storage container shown in FIG. 1.

FIG. 8 is a perspective view of a second embodiment for a combined product display and storage container.

FIG. 9 is a right-side elevation view of the product display and storage container shown in FIG. 8.

FIG. 10 is a left-side elevation view of the product display and storage container shown in FIG. 8.

FIG. 11 is a front elevation view of the product display and storage container shown in FIG. 8.

FIG. 12 is a rear elevation view of the product display and storage container shown in FIG. 8.

FIG. 13 is a top plan view of the product display and storage container shown in FIG. 8; and,

FIG. 14 is a bottom plan view of the product display and storage container shown in FIG. 8.

The broken lines represent portions of the product display and storage container that form no part of the claimed design.

1 Claim, 10 Drawing Sheets
